SEALING MEANS FOR ROTARY REGENERATIVE HEAT EXCHANGER

Charles A. Lyle and Robert H. Muller, Wellsville, N.Y.,
assignors to The Air Preheater Corporation, New
York, N.Y., a corporation of New York

Filed Mar. 5, 1957, Ser. No. 643,985

3 Claims. (Cl. 257—269)

The present invention relates to rotary regenerative heat exchange apparatus and particularly to an improvement in such apparatus used to transfer heat between waste gases and compressed air in a gas turbine cycle.

In a rotary regenerative heat exchanger a mass of heat storing material is carried in a rotor so that the material is first exposed to hot gases directed through and then is subsequently positioned in the path of a stream of air or other fluid to be heated. Because the fluid to be heated in such a cycle is sometimes highly compressed, the fluid entrained in the rotor upon entering the waste gas or low pressure stream expands into the gas and displaces a large portion thereof. This results in a substantial loss of efficiency because the work required to compress the air entrained in the rotor is lost for each turn of the rotor.

It is therefore an object of the present invention to provide means substantially reducing the amount of high pressure fluid lost due to entrainment in the rotor while simultaneously reducing the direct leakage between the high and low pressure fluid streams.

The invention will be better understood upon consideration of the following detailed description of an illustrative embodiment thereof when read in connection with the accompanying drawing in which:

Figure 1 is an elevation, partially in section, of a rotary regenerative heat exchanger embodying the present invention.

Figure 2 is a plan view of the rotor as seen from section lines 2—2.

Figure 3 is a sectional elevation of the sealing means illustrated at 3—3 of Figure 2.

In the drawings the numeral 10 designates a cylindrical shell of a rotor peripherally supported at 11 and rotated about its axis by a motor and reduction gearing 13. The rotor is adapted to carry a mass of regenerative heat transfer element 14 which first absorbs heat from the hot gases entering the heat exchanger through a duct 15 from a combustor or other heat source, and after traversing the flow passageways 19 in the element 14 the then cooled gases are discharged through an outlet duct 16. As the rotor is turned about its axis the heated element is moved into a stream of relatively cool compressed air supplied through a duct 17. After flowing over the heat transfer material 14 and absorbing heat therefrom the stream of heated air is conveyed outward through the outlet duct 18 to a predetermined point of usage.

The heating material 14 is arranged in axial banks to provide a multiplicity of separate passages 19 therethrough generally coaxial with the axis of the rotor. The heating element which provides these passages terminates in planes at either end of the rotor to form sealing faces 20A and 20B which provide the sealing surfaces against which oppositely disposed sealing means 22A and 22B are biased whereby they may direct the high pressure air or other fluid to and through the rotor. In order that streams of gas or air may not bypass the

2

heat transfer material carried by the rotor by flowing through the annular clearance space between the rotor and the enclosing housing structure 24, additional sealing means in the form of circumferential members 26 are provided around the periphery of the rotor. The sealing means 26 may be any of various conventional types which permit extensive distortion of the rotor and while illustrated as of the labyrinth type they need not be limited thereto.

10 The sealing members 22A and 22B are similarly formed annular members having one or more annular grooves 27 formed in each face 28 which lies adjacent the rotor sealing surfaces 20A and 20B. The opposite side 32 of each annular member is attached to an extensible duct 34 which may be arranged to hold each sealing member against or at a fixed distance from its adjacent rotor surface. The distal end of each bellows 34 is in turn fixed to the inlet duct for a high pressure fluid on one side and to the outlet duct for said fluid on the opposite side whereby fluid from inlet 17 may be directed through the passages 19 in the intervening rotor to outlet duct 18. The sealing means 22A and 22B in cooperation with the adjacent sealing surfaces of the rotor preclude the passing of excessive fluid therebetween into the low pressure gas duct 15, 16, and they simultaneously serve as fluid flow passageways which permit the equalization of fluid pressure between the sealing means and the rotor in the manner now described.

20 The annular sealing members 22A and 22B are provided with one or more annular grooves 27 which serve as fluid passageways to permit the free flow of fluid entirely therearound. By so doing high pressure fluid trapped in the matrix passageways 19 between the annular sealing means 22A and 22B and lying beyond the high pressure duct 17, 18 in the direction of rotor rotation is permitted to flow rearwardly to the relatively low pressure matrix passageways lying between said sealing means in advance of said duct. By this arrangement the carry-over of high pressure fluid entrapped in the rotor is minimized in accordance with the U.S. patent to Holm 2,540,733 of February 6, 1951.

30 Moreover, direct leakage between the sealing members and the rotor is decreased substantially because of the labyrinth effect produced by each concentrically grooved sealing shoe 27 in cooperation with the plane surface of the rotor.

40 Thus, as the rotor is turned about its axis hot gases at low pressure flow from inlet 15 through the passageways 19 in heating element 14 which lies outside the periphery of annular sealing members 22A and 22B and impart heat thereto and as the rotor is turned further about its axis by driving means 13 the heated element is moved into the space between sealing members 22A and 22B in alignment with ducts 17 and 18 whereby relatively cool compressed air from inlet 17 is directed through the heated element 14 to the outlet duct 18, and on passing through the heated element the compressed air absorbs heat therefrom in an amount dependent upon various predetermined design criteria such as air and gas temperature and the rotational speed of the rotor.

50 While this invention has been described with reference to the embodiment illustrated in the drawing it is evident that numerous changes may be made without departing from the spirit of the invention, and it is intended that all matter contained in the above description or shown in the accompanying drawings shall be interpreted as illustrative and not in a limiting sense.

55 What we claim is:

60 1. Heat exchange apparatus including a rotor containing a mass of regenerative heat exchange material defining a multiplicity of passageways extending axially

therethrough with opposite ends of said regenerative mass being disposed in parallel planes lying normal to the rotor axis; first inlet and outlet ducts at opposite ends of the rotor adapted to direct a low pressure fluid therethrough; second inlet and outlet ducts at opposite ends of the rotor lying eccentric to the rotor axis adapted to direct a high pressure fluid through that portion of the rotor lying therebetween; and sealing shoes surrounding the second inlet and outlet ducts bearing frictionally against opposed surfaces of said rotor to isolate the high pressure fluid from the remainder of the matrix, said sealing shoes including concentrically disposed annular grooves in the face thereof contacting the rotor whereby high pressure fluid entrained in the matrix between sealing shoes beyond the second duct is direct to the matrix between sealing shoes in advance of said duct.

2. Heat exchange apparatus including a rotor containing a mass of regenerative heat exchange material defining a multiplicity of axially disposed passageways extending therethrough with the opposite ends of said regenerative mass being disposed in parallel planes lying normal to the rotor axis; first inlet and outlet ducts at opposite ends of the rotor adapted to direct a first fluid therethrough; second inlet and outlet ducts at opposite ends of the rotor positioned eccentrically to the rotor axis to direct the flow of a second fluid through a portion of the rotor therebetween; sealing shoes encircling the second inlet and outlet ducts held in sealing relation with the regenerative mass to preclude leakage of fluid between the first and second ducts, said sealing shoes having endless groove means in the surface thereof encircling the second inlet and outlet ducts and confronting the end faces of said regenerative mass adapted to provide a labyrinth sealing effect and simultaneously afford flow passageways for the flow of fluid between arcuately spaced 35

portions of the regenerative mass intermediate the sealing shoes.

3. Heat exchange apparatus including a rotor containing a mass of regenerative heat exchange material defining a multiplicity of axially disposed passageways extending therethrough with the opposite ends of said regenerative mass being disposed in parallel planes lying normal to the rotor axis; first inlet and outlet ducts at opposite ends of the rotor adapted to direct a first fluid therethrough; second inlet and outlet ducts at opposite ends of the rotor positioned eccentrically to the rotor axis adapted to direct a second fluid through the portion of the rotor therebetween; sealing shoes encircling the second inlet and outlet ducts having plane faces biased into sealing relationship with the end faces of the regenerative mass to preclude fluid flow between the first and second ducts, said sealing shoes having concentric annular grooves in the plane faces thereof confronting axially opposite end faces of said regenerative mass adapted to provide a labyrinth sealing effect and simultaneously afford flow passageways permitting flow of fluid between portions of the regenerative mass intermediate the sealing shoes.
